UNITED STATES PATENT OFFICE.

CHARLES R. BROWN, OF NEWTON, MASSACHUSETTS.

DESIGN FOR A SLIVER STOPPING AND GUIDING SPOON.

SPECIFICATION forming part of Design No. 29,536, dated October 25, 1898.

Application filed September 30, 1898. Serial No. 692,348. Term of patent 14 years.

To all whom it may concern:

Be it known that I, CHARLES R. BROWN, of Newton, in the county of Middlesex and State of Massachusetts, have invented and produced a new and Original Design for Sliver Stopping and Guiding Spoons, of which the following is a specification, reference being had to the accompanying drawings, forming a part thereof.

10 Figure 1 of the drawings is a right-side-up perspective view of a stopping and sliver-guiding spoon, showing my new design. Fig. 2 is a view similar to that of Fig. 1, but showing the spoon in reversed or upside-down position. 15 Fig. 3 is a side view of the same arranged in horizontal position.

As shown in the drawings, the leading feature of my design consists of the downwardly curved or rounded sides *a* of the shank *b* and 20 the lugs *c c*, extending downward parallelly from the front ends of the downwardly-curved sides, and the lugs *d d*, which likewise extend

downward parallelly from the rear ends of the said sides. The inner surface *e* of the shank *b* and sides *a* conforms to the form of the outer 25 surface.

The spoon proper has its upper edges *f f* rounded, and the sides of the spoon are turned upward parallelly, while the bottom of the spoon both outside and inside is rounded on 30 concentric lines. The end of the shank *b* is upturned, as desired.

Having explained the design produced by me, I declare that what I claim is—

The design for a sliver stopping and guid- 35 ing spoon, as herein shown and described.

In testimony whereof I have signed my name to this specification, in the presence of two subscribing witnesses, this 11th day of July, A. D. 1898.

CHAS. R. BROWN.

Witnesses:

CHARLES MILLS,
LOREN W. PENNEY.
